(57) **CLAIM**

The ornamental design for a head-mounted display device, as shown and described.

DESCRIPTION

FIG. 1 is a top right front perspective view of a head-mounted display device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is another top right front perspective view thereof, in which a head attachment means in dot-dash broken lines is provided to illustrate an example environment.

The short dash-dot broken lines in the drawings represent portions of the head-mounted display device that form no part of the claimed design. The dot-dash broken lines showing of a head attachment means in FIG. 8 is for the purpose of illustrating environmental structure and forms no part of the claimed design.
